TROLLING DEVICE

Allen M. Davidson, South Bend, Ind.

Application January 25, 1945, Serial No. 574,562

6 Claims.

(Cl. 43—4)

This invention relates to trolling devices, and more particularly is concerned with a compact, adjustable trolling device for supporting a fish pole or the like from any desired position from within a boat, such as a row boat, canoe or the like, so that one individual may both row the boat and troll.

The present invention is an improvement upon the construction disclosed in Davidson et al. Patent No. 2,317,445, issued April 27, 1943.

It is one of the primary objects of the present invention to provide a device of this character which is adjustable to support the rod at any desired angle of elevation and at any desired position relative to the seat of the boat for holding the rod in proper position and yet accommodating ready removal of the fish pole from its support in case of a strike.

Another object of the present invention is to provide means for holding the butt end of the fish pole in position for trolling operation at any desired angle and elevation, but which is capable of immediate release of the rod so that it may be rocked out of the holder without any necessity of adjusting or releasing any mechanism.

Still another object of the present invention is to provide a fish pole supporting mechanism of this class in which the reel will be positioned away from the supporting device so as to allow free action thereof during fishing.

A still further object of the invention is to provide adjustable means whereby, if desired, the pole may be securely locked in the supporting device to prevent its release except by lifting the pole forward or outwardly and upwardly.

It is a further object of the present invention to provide a simplification of design and reduction in size and weight of the parts used without detracting in any manner from the required strength and rigidity of the unit as a whole, thereby providing a secure method of supporting the rod or pole in the rod holder, and eliminating any possibility of lateral movement of the rod at its forward points of support. This is accomplished by the use of a wedge-shaped grip seat wherein in combination with the socket for the butt and the butt roller support the butt of the rod is laterally centered and firmly held in place in the supporting body. This maintains an upright position of the reel on the pole by the pressure of the rod in the V or wedge-shaped support, thus eliminating the necessity of such construction to support the reel against turning over.

Other objects and advantages of the present invention will appear more fully from the fol-

lowing detailed description which, taken in conjunction with the accompanying drawings, will disclose to those skilled in the art the particular construction and operation of a preferred form of the present invention.

In the drawings:

Figure 1 is an elevational view of the device, partly in section, illustrating it mounted in operative position;

10 Figure 2 is a top plan view of the mechanism when folded for carrying purposes;

Figure 3 is an end elevational view, partly in section, showing the rod supporting means; and

15 Figure 4 is a detail elevational view of a modified type of construction.

Referring now in detail to the drawings, a boat seat is indicated fragmentarily at 5 in Figure 1 and has, as is customary, a transverse edge portion 6 to which the trolling device is adapted to be attached.

The trolling device comprises a body member 7 having at one end thereof a wing clamp nut 8 which is adapted to clamp to the end of the body member 7, the spring clamp fingers 9 and 10.

25 As shown in detail in Figure 1, the clamp fingers are arranged to clamp the body member below the plane of the seat, although it is obvious that the clamp can be reversed in position to raise the device into the plane of the seat if so desired.

30 The body member 7 at its opposite end is provided with a hinge 12, the opposite hinge element 13 thereof being secured to a depending strut member 14, which member carries at its lower end a pointed spud 15 adapted to be pressed into the floor 16 of the boat.

35 It is thus apparent that the member 14 can be swung into position as shown in Figure 1, and the spud 15 is carried in a longitudinal slot 17 formed in the member 14, being adapted to be clamped in position by the wing nut 18 and the clamping bolt 20 with the associated washer and carrier member 19.

40 Secured to the lower surface of the body member 7 as by means of the screws 22 is a resilient case or clip member 23 which is adapted to receive the spud member 15 for holding this member and the strut 14 in folded position when the device is not in use.

45 Mounted for longitudinal sliding movement on the body portion 7 of the device is the rod supporting or carrier member 25. This member is supported by means of the sliding fibre washer members 26 and 27 engaging the opposite defining surfaces of a narrow longitudinal slot 28 formed in the body portion 7. The elements 26

and 27 are frictionally clamped on opposite sides of the body member 7 by means of the wing nut 29 carried by the stud 30, which stud extends through the carrier member 25 and thence through the slot 28. Tightening of the nut 29 locks the member 25 in any adjusted position along the slot 28, thereby moving the member 25 toward or away from the boat seat 5. In addition, this mechanism also provides for clamping the carrier member 25 in any angular position relative to the longitudinal extent of the body member 7 so that the pole may be swung laterally toward either side of the boat, or may be directed straight rearwardly.

The carrier member 25 is provided intermediate its ends in the upper surface thereof with a socket portion 32, which portion is disposed slightly ahead of the stud 30 and is adapted to receive the butt end 33 of the handle portion 34 of a fish pole indicated generally at 35. The fish pole 35 is adapted to receive a reel 36 which may be secured thereto in any desired manner and which, it will be noted, is disposed forwardly of the front end of the carrier 25.

At the forward end of the member 25 there is provided a transverse stud 36 which, as shown in Figure 3, extends through the member 25 and at its opposite end is threaded to receive the wing nut 37.

Mounted by means of the stud 36 on the forward end of the carrier 25 are two parallelly extending strut members 38 which, through suitable washers, may be frictionally clamped in any desired angular position relative to the plane of the member 25. Preferably, the strut members 38 intermediate their ends are provided with a spacer 39 held in position by the bolt 40 for holding the members 38 in fixed parallel relationship.

At their upper ends the strut members 38 are each provided with conically shaped pole-supporting members 42 which face toward each other and which are clamped to the upper ends of the strut members 38 by means of the bolts 43 and the nuts 44. As will be apparent from Figure 3, this arrangement provides a wedge-shaped seat or supporting saddle for receiving the handle portion 34 of the pole, the variation in diameter of the handle portion 34 being taken care of by the conical surfaces of the members 42.

Adjacent the rear end of the carrier member 25 there is provided a transverse slot 45 which preferably is elongated in a longitudinal direction and receives the transverse pin 46 shown in Figure 2. The pin 46 is threaded to receive a wing nut 47 for the purpose of clamping in adjusted angular position thereon a pair of parallel strut members 48 which, at their free ends, are connected together by a roller member 49 which preferably has the central portion thereof reduced as indicated at 50 to provide a tapered roller construction of hour-glass shape.

When the pin 46 is in its rearmost position in the slot 45, as shown in Figure 1, the strut members 48 may be rotated forwardly to dispose the roller 49 in position, engaging over the butt end 33 of the pole 35. In this position the strut members 48 may be frictionally clamped by means of the wing nut 47, and will hold the pole 35 against rocking about the support members 42 and resisting any downward movement of the tip end of the pole. However, when a strike occurs and the fish attempts to run with the line, it is readily apparent that by grasping the handle portion 34 of the pole and rocking it upwardly and rearwardly, the pole can be readily removed from the sup-

porting device, the butt end 33 thereof rocking out of the socket 32 so that the pole may be entirely removed.

However, if the pin member 46 is moved to the forward end of the slot and the roller 49 is then clamped in position over the butt end of the pole as shown by dotted lines in Figure 1, the roller is disposed beyond the rocking point of the butt end 33 of the pole in the socket 32, and consequently locks the pole against removal except by lifting the pole forwardly or outwardly when the pin member 46 is clamped in its forward position.

Thus, it will be apparent that with this construction the pole holding support provided by the carrier member 25 can be arranged to allow ready removal of the pole by the fisherman or can be arranged to lock the pole firmly in position against accidental displacement, but can be removed only by a forward or outward movement and then a lifting movement.

Considering now Figure 4, in this form of the invention I have disclosed a construction in which the cone-shaped members 42 carried by the strut members 38 may have their lateral spacing adjusted by means of oppositely threaded portions 50 and 52 of a spindle member 53 having the flattened end portion 54 for manual operation. This operates in somewhat the same manner as a turnbuckle so that when rotated in one direction, the members 42 are spread apart, if desired, for receiving a pole having a handle portion of larger diameter. Conversely, when the member 53 is rotated in the opposite direction the lateral spacing between the members 42 is decreased, thereby arranging the device for holding the pole having a handle portion of smaller diameter.

It is therefore believed apparent that I have provided for various adjustments of the device for receiving poles having handle portions of different diameters, and for also providing a device wherein the butt end of the pole may be fixed in position or may be merely clamped for support but providing for removal of the pole when desired. The adjustment of the carrier member 25 allows a great range of flexibility in the positioning of the pole, while the supporting body member 7 and strut 14 insure the support of the device in any desired position with reference to a boat seat.

While I am aware that various changes may be made in certain of the details herein shown and described, I do not intend to be limited except as defined by the scope and spirit of the appended claims.

I claim:

1. A trolling device comprising a generally longitudinal body portion, means at one end for frictionally clamping said body portion to a boat seat, means at the other end thereof for supporting said end from the floor of the boat, a carrier member pivotally mounted on said body portion, a pivotally mounted butt-clamping roller at one end of said carrier member, a butt-receiving socket in said carrier member forwardly of said roller for receiving the butt end of a fish pole, said roller being movable into position over the butt end of said pole when disposed in said socket, and pivotally mounted means disposed at the forward end of said carrier member including laterally spaced tapered support members receiving the handle portion of said pole intermediate said butt end and the reel seat thereof, said last-named means being frictionally clamped

in adjusted position to determine the elevation of said pole.

2. The device of claim 1 wherein said roller is so disposed relative to said socket that the butt end of said pole can be rocked out of position in said socket upon raising the tip end of the pole.

3. The device of claim 1 wherein the pivotal mounting of said butt-clamping roller can be adjusted longitudinally of said carrier member.

4. The device of claim 1 including means carried by said pivotally mounted means at the forward end of said carrier member for varying the lateral spacing between said tapered support members.

5. The device of claim 1 wherein said laterally spaced tapered support members comprise inwardly facing cone-shaped discs.

6. In a trolling device including a body portion adapted to be supported horizontally in a boat, a carrier member pivotally mounted thereon for lateral swinging movement and longitudinal adjustment, a socket in the upper face of said carrier member intermediate the ends thereof for receiving the butt end of a fish pole, a pivotally mounted butt-clamping member at one end of said carrier member having a transverse roller movable into position over the butt end of said pole, and supporting means pivotally mounted at the opposite end of said carrier member, including transversely spaced means forming a seat for the portion of the fish pole intermediate the butt-end and reel seat thereof, said last-named means being frictionally clamped in position to provide for predetermined elevation of said pole.

ALLEN M. DAVIDSON.
